UNITED STATES PATENT OFFICE.

WILLIAM F. CASH, OF HIAWATHA, KANSAS.

QUILTING-FRAME.

No. 884,793.

Specification of Letters Patent. Patented April 14, 1908.

Application filed December 15, 1906. Serial No. 347,958.

To all whom it may concern:

Be it known that I, WILLIAM F. CASH, a citizen of the United States of America, residing at Hiawatha, in the county of Brown 5 and State of Kansas, have invented new and useful Improvements in Quilting-Frames, of which the following is a specification.

My invention has relation to quilting frames and it consists in the construction 10 and arrangement of parts which will be hereinafter described and particularly pointed out in the claim.

In the accompanying drawing:—Figure 1 15 is a perspective view of a quilting frame made in accordance with my invention. Fig. 2 is a detail sectional view showing the manner of mounting one of the take-up rollers in the side bar of the quilting frame.

Referring to the accompanying drawing 20 for a more particular description of my invention, the numerals 1 and 2 designate the side rails of the quilting frame. Mounted in the ends of said rails 1 and 2 is a roller 3 covered with any suitable material, said roller 25 having a ratchet wheel 4 secured to the outer end thereof and a pawl 5 pivoted to the side rail 2 for engaging the teeth of the ratchet wheel 4. A similar roller 6 is journaled in the opposite ends of the side rails 1 and 2, 30 and a ratchet wheel 7 on the end of the shaft of said roller is provided with peripheral ratchet teeth engaged by a pawl 8 pivoted at 9 to the side rail 2. A take-up roller 10 is removably journaled in the side rails 1 and 35 2 by means of a notch 11 in the rail 1 in which is seated the end 12 of the shaft of said roller, and the opposite end of said shaft is seated in a notch 13 in the side rail 2, and said shaft is held in the notch by means of a 40 pivoted or hinged bearing strap 14 hinged at 15 to the top of the rail 2 and provided with a downwardly projecting portion 16 which bears on the top of the shaft 11, the terminal end of said bearing strap being provided

45 with a toe 17 which is engaged by a pivoted latch 18 for holding said bearing strap in position to secure the shaft 11 within the notch 13. Whenever it is required to remove the roller 10 the bearing strap 14 may 50 be thrown out of the notch by moving the pivoted latch 18 in an obvious manner. On the outer end of the shaft 11 a ratchet wheel

19 is secured and a pawl 20 pivoted to the rail 2 engages the ratchet teeth on said ratchet wheel.

To suspend the quilting frame I provide curved arms 20' one end of each of which is pivoted to the opposite sides of the rails 1 and 2, the opposite end of these arms is secured to the opposite ends of a spreader bar. 60 A bail 21 has its ends secured to said spreader bar and said bail is bent at its central portion to form a loop 24.

The numeral 25 designates a carriage provided with Y-shaped arms 25' to which is secured a vertical depending bar 30, having a series of hooks 25, secured thereto and arranged one above the other to permit of the quilting frame being adjusted upwardly or downwardly by means of the loop 24 engaging any one of hooks. The upper ends of the arms 25' are provided with a cross-bar 25", having bearings 26, at opposite ends in which is mounted rollers 26' which serve to travel upon a wire 27 stretched across a room to 70 permit the quilting frame being shifted to proper position as may be required during the quilting operation.

The side rail 1 may be provided with a hinged section 28 for permitting the roller 3 80 to be detached therefrom whenever required at one end, and said hinged section being provided with a metal strap *a*, and the pintle *b* of the hinge *c* passes through said strap to hinge the section 28 to the section 1, a suitable clip 85 29 being pivoted to the section 1 to hold said two sections in adjusted position.

From the foregoing it will be obvious that a quilting frame made in accordance with my invention, may be suspended at the required 90 height and moved about in any direction or tilted to present the quilt at the proper position for forming the cross lines of stitching therein.

Having thus described the invention, what 95 I claim is:

A quilting frame comprising side rails with rollers pivoted to each of their opposite ends, an intermediate detachable roller, curved arms each having an end pivoted to the side 100 rails, a spreader bar arranged above the center of the frame and having the opposite ends of the arms secured thereto, a bail secured to the spreader bar and having its central por-

tion bent to form a loop, a carriage provided with V-shaped arms having a bar depending therefrom, a cross-bar secured to the upper ends of the arms and provided with bearings 5 in which are mounted rollers serving to travel on a suitably arranged wire, said depending bar being provided with a series of hooks arranged one above the other, and said loop serving to engage the hook to permit of the

quilting frame being vertically adjustable, 10 substantially as specified.

In testimony whereof, I affix my signature in presence of two witnesses.

WILLIAM F. CASH.
